UNITED STATES PATENT OFFICE.

WILLIAM W. JOHNSON, OF MEMPHIS, TENNESSEE.

ICE-CAN BRACKET AND DROP TUBE.

Application filed July 20, 1927. Serial No. 207,160.

The present invention is concerned with the provision of a bracket adapted to be used for supporting the drop tubes in the ice cans when blowing raw water ice. The 5 bracket also serves to retain the ice can in proper position during the ice making period.

An object of the invention is to provide a bracket of this character which will serve 10 to firmly retain an ice can against the bottom of the freezing tank or flatly against a timber which may be laid on the freezing tank bottom, so that the blocks of ice will be square topped.

15 A further object of the invention is to provide a bracket which will effectively prevent the water filled ice can from floating in the brine, and will thereby greatly expedite the freezing of the water in the can.

20 Still another object of the invention is to provide a bracket supporting the drop tubes in such a manner that the tubes are self-centering, being mounted for a free pendulum-like swinging movement, and finding 25 the center of the can by gravity.

Other objects of the invention are to provide a bracket of simple, practical construction which will be rugged, durable and efficient in use, which may be conveniently 30 utilized for retaining conventional types of ice cans in conventional types of frames, which may be applied or removed with ease and expedition, and which may be manufactured and installed with comparative 35 economy.

With the above noted and other objects in view, the invention consists in certain novel features of construction and combinations and arrangements of parts, as will 40 be more fully hereinafter set forth and pointed out in the claims. The invention may be more fully understood from the following description in connection with the accompanying drawings, wherein—

45 Figure 1 is a fragmentary view in vertical section through the upper portion of an ice can and its supporting frame timbers, showing one of the brackets of the present invention in use, and a drop tube supported 50 thereby;

Figure 2 is a perspective view of the bracket; and

Figure 3 is an enlarged vertical sectional detail on the line 3—3 of Figure 1.

In the drawings I have used the reference 55 character 10 to designate the conventional rectangular supporting frame formed of timbers within which an ice can 11 is adapted to be retained during the freezing operation. It is understood that the frame 10 60 will be supported adjacent the surface of the brine in the brine tank, and the can 11 will dip into the brine. The cans are provided with oppositely disposed round openings 12 adjacent their upper edges, these openings 65 being formed to permit the engagement of a lifting tool with the can when removing the latter from a brine tank, and extending through the usual can bands 13 just above the upper ends of the usual instruck 70 strengthening ribs or corrugations 14.

The bracket of the present invention includes a generally cylindrical shank portion 15 terminating in a reduced end 16 of circular cross section adapted to pass 75 through one of the openings 12 and enter a socket 17 in the frame 10. To prevent wear on the frame this socket is preferably lined with a metal wear sleeve 18. It will be understood that the diameter of the reduced extension 16 is such that the extension 80 may be readily slipped through the opening 12 and into the socket. The extension defines a shoulder 19 which is adapted to abut the inner face of the ice can 11 around the 85 opening 12.

The bracket shank inclines downwardly as indicated at 20, terminating in a flat offset and slightly downwardly inclining substantially horizontal portion 21 adapted for 90 disposition over the center of the can. The portion 21 of the bracket only assumes a true horizontal position when the can has floated up and slightly lifted the free end 95 of the bracket by its engagement with the bracket extension 16. An opening 22 in the flat end 21 of the bracket includes a bevelled mouth 23 centering and providing a seat for the rounded lower end 24 of a ferrule 25. This ferrule is adapted for attachment to 100 an air line (not shown), and carries a drop tube 26 passed through the opening in the bracket. To facilitate the connection of the air line a tapered socket 27 is provided 105 in the top of the ferrule.

The distance from the shoulder 19 to the center of the opening 22 is exactly half the width of the can, so that when the drop tube

is inserted through the opening 22 it will be centrally disposed. The round bottomed ferrule rocking in the flared mouth of opening 22 has a free swinging movement to find its own final position by gravity, and this position will necessarily be at the exact center of the can to promote uniform agitation and freezing.

In order to promote the equal distribution 10 of air in all directions from the lower discharge end of the drop pipe 26, the lower end of the pipe is preferably provided with a series of equidistantly spaced upwardly extending air-discharging slots 28 through 15 which the air escapes.

From the foregoing description it will be apparent that the bracket offers a means for securely holding the ice can down against the tank bottom or against timbers on the 20 bottom in an absolutely level position, so that the block of ice produced will be square topped. It also overcomes any tendency of the can to float in the brine, and expedites the freezing of the water in the can. It can 25 be cheaply constructed and may be quickly applied, and the drop pipe which it carries quickly inserted or removed.

Obviously, various changes and alterations might be made in the general form and 30 arrangement of parts described without departing from the invention. Hence I do not wish to limit myself to the details set forth, but shall consider myself at liberty to make such changes and alterations as 35 fairly fall within the spirit and scope of the appended claims.

I claim:

1. An ice can bracket including a shank, a reduced portion at one end of the shank 40 adapted to pass through the opening in an

ice can and enter an opening in a can supporting frame, the reduced extension defining a shoulder on the shank adapted to abut the inner face of an ice can, the opposite end of the shank being offset and having an 45 opening therein adapted to receive a drop tube.

2. An ice can bracket including a shank, a reduced portion at one end of the shank adapted to pass through the opening in an 50 ice can and enter an opening in a can supporting frame, the reduced extension defining a shoulder on the shank adapted to abut the inner face of an ice can, the opposite end of the shank being offset and having 55 an opening therein adapted to receive a drop tube, the mouth of the opening being flared and permitting rocking of the round-bottomed tube-supporting ferrule, whereby the tube may have a pendulum-like swinging 60 movement and find the center of the can by gravity.

3. In a brine tank assembly, including a can frame and a can in the frame, a bracket having at one end a member passing through 65 the side of the can and into the frame, whereby to prevent the can from floating, the free end being offset, said offset end being flattened and disposed over the center of the can and having a drop tube opening therein. 70

4. In a brine tank assembly, a can frame, a can in the frame, a can bracket, one end of said bracket passed through said can and into the frame to prevent the can from floating, the free end of the bracket offset, a 75 drop tube suspended from said offset bracket end, and disposed substantially centrally of the can.

WILLIAM W. JOHNSON.
